INSECT DEFLECTOR FOR AUTOMOBILES

James I. Hoag, Newton, Iowa

Application May 29, 1939, Serial No. 276,271

3 Claims. (Cl. 296—91)

My invention relates to the art of deflectors to be attached to the front of an automobile for creating air currents upwardly and over the automobile windshield. Such devices now in common use are made of metal or other stiff material.

The object of my invention is to provide a deflector of this class to be used as an advertising novelty and made of a flat sheet of cardboard which is well adapted for printing or lithographing and which is inexpensive enough for use as an advertising novelty.

More specifically, it is my object to provide simple and inexpensive means for strengthening and reinforcing the relatively bendable sheet of cardboard throughout its entire area so that it will withstand the pressure of air currents when used on an automobile at high speed.

In the accompanying drawing:

Figure 1 shows my deflector in the form of a flat sheet of cardboard before being shaped;

Figure 2 shows a similar view shaped and held in its finished form;

Figure 3 shows a transverse sectional view on the line 3—3 of Figure 2;

Figure 4 shows a transverse sectional view on the line 4—4 of Figure 2;

Figure 5 shows a longitudinal sectional view on the line 5—5 of Figure 2;

Figure 6 shows a side view of a portion of an automobile having my deflector applied thereto; and

Figure 7 shows a perspective view of the metal clip.

Figure 8 is a detail view of the spring hook for attaching the deflector to the automobile.

The body 10 of the deflector is formed of a sheet of cardboard substantially heart-shaped in outline. This material is desirable because I am using these deflectors as advertising novelties, and printing or lithographing may be done on cardboard cheaply and effectively. I first form weakened lines in the sheet by scoring or bending the sheet along a line 11 extending from the lower central edge of the sheet longitudinally to a point 45 near the upper edge, and another weakened line 12 transversely of the sheet near its upper central portion.

At the lower side portions of the sheet are the openings 13 to receive supporting hooks.

50 In the flat state of the sheet of cardboard it is so bendable that it would not withstand the air pressures to which it is subjected when in use, and would collapse and bend rearwardly.

I strengthen and reinforce the sheet and at the 55 same time shape it to direct air currents in the

proper direction as follows: I grasp the sheet at about the location of the openings 13 and move the lower side portions of the sheet toward each other. This automatically produces the following shaping, strengthening and reinforcing. Due to the weakened lines, the lower longitudinal central portion is formed into a forwardly extended ridge 14, and this ridge at its lower end has the adjacent portions of the sheet parallel and in engagement with each other, as shown at 15 in Figure 3. This same movement which makes the ridge 14 also bends the side portions of the sheet forwardly, as shown at 16 in Fig. 4. At the same time the entire upper portion of the sheet above the line 12 is bent forwardly, as shown at 17 in Fig. 6, forming with the upper portion of the ridge 14 an obtuse angle, as shown at 18 in Fig. 5.

For the purpose of securely holding the sheet in the form just described I apply a metal clip 19 to the lower portion of the ridge 14, as shown in Fig. 3.

To secure the deflector to an automobile I use the spring hooks 20 shown in Fig. 8, and extend the hooks through the openings 13 and around a part of the automobile grill. These spring hooks 25 are in common use and are well known.

In practice I have demonstrated that the completed cardboard sheet is sufficiently braced and reinforced to withstand the pressures to which it is subjected when in use; the forwardly extended 30 ridge 14 prevents the lower portion of the sheet from bending rearwardly or forwardly, the forward curvature of the side edges braces them against bending rearwardly, the forward bending of the upper portion of the sheet above the line 35 12 braces it against bending rearwardly.

All of this shaping is accomplished by first forming the weakened lines 11 and 12 and then simply moving the lower side portions of the sheet toward each other and permanently holding them 40 in this position by the clip 19.

I have demonstrated that the cardboard is so inexpensive and the operations for forming the completed deflectors so simple, that the deflectors can be successfully produced and distributed as 45 an advertising novelty.

I claim as my invention:

1. An insect deflector for automobiles, formed of a flat body portion of bendable, resilient cardboard or the like, having a weakened line at its 50 longitudinal center extended to a point slightly spaced from its top edge and another weakened line extended transversely near its upper edge, the two lower side portions of the sheet having been forced against the resiliency of the sheet 55

- in a direction toward the weakened central line whereby a ridge is formed having its opposite side members in engagement with each other, and whereby the upright side edge portions of the sheet are curved outwardly and forwardly and thereby braced by the resiliency of the sheet against being bent rearwardly by air pressure, and whereby the top edge portion of the sheet above the weakened horizontal line is inclined forwardly and thereby braced by the resiliency of the sheet against being bent rearwardly by air pressure, and a metal clip applied to the said ridge for holding the side portions thereof firmly together. 5
- 10 2. An insect deflector for automobiles, formed of a flat body portion of bendable, resilient cardboard or the like, the two lower side portions of the sheet having been forced against the resiliency of the sheet in a direction toward the longitudinal central portion, whereby a ridge is formed having its opposite side members in engagement with each other, and whereby the upright side edge portions of the sheet are curved outwardly and forwardly and thereby braced by the resiliency of the sheet against being bent rearwardly by air 15 pressure, and whereby the top edge portion of the sheet is inclined forwardly and thereby braced by the resiliency of the sheet against being bent rearwardly by air pressure, and a metal clip applied to the said ridge for holding the side portions thereof firmly together. 20
